COMBINED DESK AND CHAIR

Bruce L. Carlson, Seattle, Wash.

Application January 28, 1957, Serial No. 44,625

Term of patent 3½ years

(Cl. D33—11)

Figure 1 is a perspective view of a combined desk and chair, showing my new design, as viewed from the left side and slightly to the rear thereof, to the interior of the desk portion thereof;

Fig. 2 is a perspective view of the same, as viewed from the right side and slightly to the front thereof; and Fig. 3 is a bottom view of the same.

The dominant features of my design are shown in full lines.

I claim:

The ornamental design for a combined desk and chair, substantially as shown and described.
